CARRYING CASE WITH FREELY HINGED CLOSURE

Leo Stein, Chicago, Ill., assignor to Stein Bros. Mfg. Co., Chicago, Ill., a corporation of Illinois
Filed Dec. 27, 1961, Ser. No. 162,602
7 Claims. (Cl. 190—48)

This invention relates to luggage and more particularly to a carrying case of the general type known as a catalogue or brief case.

An objective of this invention is to provide an improved carrying case that is not only stronger, but allows the flap closure to open out fully and easily, and yet is more economical to manufacture.

Another objective of this invention is to provide an improved carrying case, of the catalogue or brief case type, having overlapping flaps, as a closure, with improved means for connecting the flaps to the sides of the case which also serves as reinforcing beads along the upper edges of the sides of the case and to resist wear.

In accordance with the general features of this invention, there is provided in a carrying case or luggage bag having sides with opposite movable closure flaps adapted to overlap each other, movable means for connecting the flaps to the sides, each comprising a pivotal hinged connection between an edge of each side and its associated flap.

Still another feature of the invention relates to the connecting of the closure flaps of the bag to the sides by means of elongated piano hinges.

Yet another feature of the invention relates to providing hinges between closure flaps and sides of a bag, each of which has hinge plates connected by a common hinge pin with the plates embedded in the sides and flaps of the bag.

A further feature of the invention relates to providing a carrying case having overlapping closure flaps with hinges, each of which includes plate portions provided with spaced holes, each of a size to receive a sewing machine needle and with the plate portions secured to the flaps and sides by stitching passing through the holes and the material of the flaps and sides.

Another and still further feature of the invention relates to the provision of a carrying case wherein upper edges of its sides are offset with relation to adjoining edges of the top closure flaps so that at each junction there is provided an elongated space in which an elongated piano hinge is disposed for connecting the flap to the side with the hinge in substantial flush relation to the adjoining exterior surfaces of the flap and side.

Another feature of the invention relates to the provision of piano hinge connections between closure flaps of a bag and adjoining sides of such construction and arrangement that the hinges perform the multi-purpose of providing for the pivoting of the flaps, of maintaining the sides of the bag vertical at the open end and of resisting collapsing of the sides.

Other objects and advantages of this invention will more fully appear from the following detailed description taken in connection with the accompanying drawings which illustrate a similar embodiment thereof; and in which:

FIGURE 1 is a perspective view of a case or bag embodying the feature of this invention and showing the upper closure flaps, when open, in dotted line positions;

FIGURE 2 is an enlarged fragmentary cross-sectional view taken substantially along the line II—II of FIGURE 1, and showing in dotted lines one of the closure flaps in open position; and

FIGURE 3 is a fragmentary plan view of a side and a flap when the latter is open in alignment with the side

2

and showing portions broken away to illustrate the hinge plate portions sandwiched between the plies of the side and flap, as well as showing the stitching through the holes in such hinge portions.

As shown on the drawings:

The carrying case or luggage bag embodying my invention is designated generally in FIGURE 1 by the reference numeral 10. With the exception of hardware, it may be made of any suitable sheet material, such for example, as multi-ply plastic material or multi-ply leather-like material. This bag has vertical sides 11 which are integrally connected through a bottom 12 so that the sides and the bottom, in reality, can comprise one sheet of material. The sides 11 are spaced apart by ends 13 suitably attached or sewn at its edges 14 to the sides and the bottom.

The upper end of this bag, while formed open, is adapted to be closed by means of overlapping closure flaps 15 and 16 comprising primarily extensions of the bag sides 11. The underlying flap 16 can be provided with a suitable handle 17 of a size to project through a slot 18 in the overlapping flap 15.

The bag may be provided with the customary hardware, such for example, as latches or locks 19—19, which may be of any conventional construction for latching or locking the overlapping flap 15 to the underlying flap 16.

The foregoing described portions of my bag are more or less conventional and my invention particularly relates to the manner in which the flaps 15—16 are attached to the parallel vertical bag sides 11.

Heretofore, it has been common practice to make the flaps integral with the sides and to depend upon the material itself to serve as a pivotal connection between the flaps and the sides. This, however, had disadvantages in that the top portions of the sides would tend to collapse. Moreover, after repeated usage, the material of the sides and flaps, at their junctions, would tend to buckle and in fact, to abrade and wear out.

Now it will be appreciated that the merchandising of bags of this type involves a highly competitive business, and that, hence, any improvements that are made must take into consideration the economy of the bag with reference to its cost of manufacture. I propose in accordance with the feature of this invention to reinforce greatly and to increase the longevity of a bag of the present character without detracting from the competitive marketing of the same.

To the foregoing end, there is provided between each flap 15—16 and the associated bag sides 11, a novel piano hinge joint designated generally by the reference character 20. Since the joint at each side is identical, a description of one will suffice for both.

The piano hinge structure 20 is more fully disclosed in FIGURES 2 and 3, and may be made of any suitable relatively rigid material, such as metal or even of strong plastic material. The hinge is of a conventional piano hinge type and embodies pivotal hinge plates 21 and 22, through aligned eyes 21a and 22a of which there is a common hinge or pivotal pin, or pintle 23.

Plate 22 of the hinge is sandwiched between plies 11a and 11b of one side 11, and sewing machine stitching 24 extends through holes 25 in the plate to fasten the plate to the plies. Similarly, the other plate 21 is sandwiched between plies 15a and 15b of a flap 15, and has stitching 26 through spaced holes 27 in the plate 21 for anchoring the plate to the flap.

The holes 25 and 27 in the hinge plates are of a size to permit a sewing machine needle to pass freely through the same as the hinge plate is being stitched in sandwiched relation to the adjoining plies of material. If it is so desired, the plies of material may be prepunched to provide holes for alignment with the holes in the

plates so as to facilitate stitching. Of course, it will be appreciated that other suitable means may be employed for fastening the hinge plates to the sides 11 and the adjoining flaps such for illustration as a plastic cement.

Now, referring particularly to FIGURE 2, it will be noted that in the case of each flap 15-16, its edge adjoining the side 11 is offset inwardly so as to define a longitudinal space 30 between the adjoining edges of each flap and side. This space is of a size to receive the hinged area of the hinges including the aligned hinge eyes or rounded hinged portions 21a and 22a so that the hinged area will appear to be substantially flush with the adjoining exterior surfaces of the flap and side.

Actually, the location of the hinge 20 in the longitudinal space 30 protects the adjoining edges of the flap and side and more important, reinforces the side at its uppermost extremity so as to resist buckling or giving in of the side. Another advantage is that each hinge serves as a buffer or bead at the top of the bag to minimize wear and tear and abrading at the upper end of the bag in the use of the same.

From the foregoing, it is clear that each hinge, which, of course, is preferably made of metal construction, not only performs the purpose of providing a pivotal connection between the bag sides 11 and the adjoining flaps, but in addition, comprises a reinforcement for resisting buckling or giving in of the side and for protecting the adjoining edges of the sides and flaps from abrading contact with other objects.

I claim as my invention:

1. In a luggage bag including multi-ply sides with opposite movable multi-ply closure flaps adapted to overlap each other to close an open end of the bag, a pivotal hinge connection between an edge of each side and an edge of its associated flap comprising an elongated piano type hinge, there being one hinge on each side of the bag at its open end, said sides and flaps being made of multi-ply sheet material and said hinge including plates connected by a common hinge pin and one plate having a portion extending between and embedded in plies of a side and the other plate having a portion extending between and embedded in plies of a flap, said plate portions each having spaced holes each of a size to receive a sewing machine needle and said hinge plate portions being secured to said flap and side by stitching passing through said holes and through the plies of said flap and side.

2. In a luggage bag including multi-ply sides with opposite movable multi-ply closure flaps adapted to overlap each other to close an open end of the bag, a pivotal hinge connection between an edge of each side and an edge of its associated flap comprising an elongated piano type hinge, there being one hinge on each side of the bag at its open end, said sides and flaps being made of multi-ply sheet material and said hinge including plates having hinge eyes connected by a common hinge pin and one plate having a portion extending between and embedded in plies of a side and the other plate having a portion extending between and embedded in plies of a flap, said plate portions each having spaced holes each of a size to receive a sewing machine needle and said hinge plate portions being secured to said flap and side by stitching passing through said holes and through the plies of said flap and sides, the hinged edges of said flap and side being offset relative to each other when the flap is in closed position, thus defining an elongated space in which the joined hinge eyes of the piano type hinge are disposed in substantially flush relation with the exterior surfaces of the flap and side.

3. In a luggage bag including multi-ply side with opposite movable multi-ply closure flaps adapted to overlap each other to close an open end of the bag, a pivotal hinge connection between an edge of each side and an edge of its associated flap comprising an elongated piano

type hinge, there being one hinge on each side of the bag at its open end, said sides and flaps being made of multi-ply sheet material and said hinge including plates having hinge eyes connected by a common hinge pin and one plate having a portion extending between and embedded in plies of a side and the other plate having a portion extending between and embedded in plies of a flap, said plate portions each having spaced holes each of a size to receive a sewing machine needle and said hinge plate portions being secured to said flap and side by stitching passing through said holes and through the plies of said flap and side, the hinged edges of said flap and side being offset relative to each other when the flap is in closed position, thus defining an elongated space in which the joined hinge eyes of the piano type hinge are disposed in substantially flush relation with the exterior surfaces of the flap and side, said hinges comprising reinforcement between the flaps and the bag sides for maintaining the bag sides at the open end of the bag vertical and to resist collapsing of said sides.

4. In a luggage bag including sides with opposite movable closure flaps adapted to overlap each other to close an open end of the bag, a pivotal hinge connection between an edge of each side and an edge of its associated flap comprising an elongated hinge, there being one on each side of the bag at its open end, said sides and flaps being made of sheet material and said hinge including plates connected by hinge means and one plate having a portion extending in lapping engagement with the sheet material of a side and the other plate having a portion extending in lapping engagement with the sheet material of a flap, said plate portions each having spaced holes each of a size to receive a sewing machine needle and said hinge plate portions being secured to said flap and side by stitching passing through said holes and through the sheet material of said flap and side.

5. In a luggage bag including sides with opposite movable closure flaps adapted to overlap each other to close an open end of the bag, a pivotal hinge connection between an edge of each side and an edge of its associated flap comprising an elongated metallic hinge, there being one on each side of the bag at its open end, said sides and flaps being made of multi-ply sheet material and said hinges each including plates connected by hinge means and one plate having a portion extending in lapping engagement between plies of the sheet material of a side and the other plate having a portion extending in lapping engagement between plies of the sheet material of a flap, said plate portions each having spaced holes, and stitching means extended through said holes and through the sheet material of said flap and side securing one of said plate portions with said flap and the other of said plate portions with said side.

6. In a luggage bag including multi-ply sides with opposite movable multi-ply closure flaps adapted to overlap each other to close an open end of the bag, a pivotal hinge connection between an edge of each side and an edge of its associated flap comprising an elongated piano type hinge, there being one hinge on each side of the bag at its open end, said sides and flaps being made of multi-ply sheet material and said hinge including plates having hinge eyes connected by a common hinge pin and one plate having a portion extending between and embedded in plies of a side and the other plate having a portion extending between and embedded in plies of a flap, said plate portions each having spaced holes, and means extended through said holes and through the plies of said flap and side securing said hinge plate portions to said flap and side, the hinged edges of said flap and side being offset relative to each other when the flap is in closed position, thus defining an elongated space in which the joined hinge eyes of the elongated piano edge are disposed in substantially flush relation with the exterior surfaces of the flap and side, said hinge plates comprising reinforcements between the flaps and the bag sides for maintaining the

bag sides at the open end of the bag vertical and to resist collapsing of said sides.

7. In a luggage bag including multi-ply sides with opposite movable multi-ply closure flaps adapted to overlap each other to close an open end of the bag, a pivotal hinge connection between an edge of each side and an edge of its associated flap comprising an elongated piano type hinge, there being one hinge on each side of the bag at its open end, said sides and flaps being made of multi-ply sheet material and said hinge including plates having hinge eyes connected by a common hinge pin and one plate having a portion extending along piles of an associated one of said sides and the other plate having a portion extending along piles of an associated one of said flaps, said plate portions each having spaced holes, and means extended through said holes and through the piles of said flap and side securing said hinge plate portions to said flap and side, the hinged edges of said flap and side being offset relative to each other when the flap is in closed position, thus defining an elongated space in which the joined hinge eyes of the elongated piano type hinge are disposed in substantially flush relation with the exterior surfaces of the flap and side, said hinge plates comprising reinforcements between the flaps and the bag sides for maintaining the bag sides at the open end of the bag vertical and to resist collapsing of said sides.
